UNITED STATES PATENT OFFICE.

BAXTER LYON, OF PROVIDENCE, RHODE ISLAND.

FISHING-ROD.

SPECIFICATION forming part of Letters Patent No. 692,884, dated February 11, 1902.

Application filed April 13, 1901. Serial No. 55,599. (No model.)

To all whom it may concern:

Be it known that I, BAXTER LYON, a citizen of the United States, residing at Providence, in the county of Providence and State of Rhode Island, have invented certain new and useful Improvements in Fishing-Rods, of which the following is a specification, reference being had therein to the accompanying drawings.

10 My invention relates to fishing-rods of every description, but is described as applied more particularly to jointed rods, and has for its primary purpose a protection against the elements, air and water, and an improved elasticity and durability.

Heretofore wooden or metal rods have been commonly used, with the result that the former has quickly become sodden or warped after fracture of the varnish coating thereon, 20 while the metal rods suffer from corrosion and rust. The great tension to which a rod is subjected in actual use requires a greater rigidity of structure in rods of such material than is consistent with the elasticity demanded by use in actual fishing.

The desired ends are attained and the recited objections avoided by the invention hereinafter described, and illustrated in the accompanying drawings, wherein—

30 Figure 1 is a side elevation of my complete rod; Fig. 2, a longitudinal central section of a joint; Fig. 3, a side view of a socket; Fig. 5, an end view of the same; Fig. 6, a side view of a ferrule fixed to a section, and Fig. 35 4 an end view of the same.

Like letters of reference refer to like parts throughout the views.

In detail the construction of my rod is as follows: A successive series of gradually-tapering rod-sections *a b* and tip *c* are formed

for assemblage into a complete rod of usual appearance, as shown in Fig. 1. Each rod-section consists of an interior tubular reinforcement of metal or wood *d*, around which rubber is vulcanized to a suitable degree of 45 elasticity. This rubber body also covers and seals the respective ends of each rod-section, protecting the interior tube *d* against water or moisture and forming a hard-rubber body *e* for the entire section. Over the larger end 50 of each section is forced a ferrule *m*, which is adapted for insertion into a plain tubular socket *n*, fixed to the smaller end of each rod-section.

Experiment shows that a pole composed of 55 a rubber body constructed as above described when reinforced by steel increases the natural flexibility of the inclosed steel tube many fold. Hence I prefer the use of steel as a reinforcing means in most cases. Furthermore, 60 it is evident that my invention is applicable to tubular rods of all descriptions. Hence I do not limit my claim to sectional rods.

Having thus described my invention, what I claim as new, and desire to secure by Letters 65 Patent, is—

A fishing-rod made up of a series of sections each section comprising a metallic tube and a coating of rubber completely incasing the tube and closing the ends thereof, where- 70 by the access of moisture to the interior as well as the exterior of the tube is prevented, substantially as described.

In testimony whereof I have affixed my signature in presence of two witnesses.

BAXTER LYON.
